CLAIM

The ornamental design for a long wing sleeping mat for camping, as shown and described.

DESCRIPTION

FIG. 1 is a top perspective view of the long wing sleeping mat for camping showing my new design.

FIG. 2 is a front view of the long wing sleeping mat for camping.

FIG. 3 is a rear view of the long wing sleeping mat for camping.

FIG. 4 is a left side view of the long wing sleeping mat for camping.

FIG. 5 is a right side view of the long wing sleeping mat for camping.

FIG. 6 is a top view of the long wing sleeping mat for camping.

FIG. 7 is a bottom view of the long wing sleeping mat for camping; and,

FIG. 8 is an enlarged view of the FIG. 2.

Any shading and cross-hatching are not features of the design but are utilized to illustrate the surface contours of the long wing sleeping mat for camping design in the drawings. The broken lines in the Figures represent the enlarged view indicating lines and boundary and form no part of the claimed design.
